CLAIM

The ornamental design of a laundry appliance, as shown and described.

DESCRIPTION

FIG. 1 is a front perspective view showing a laundry appliance;

FIG. 2 is a front elevational view of the laundry appliance shown in FIG. 1;

FIG. 3 is a top plan view of the laundry appliance shown in FIG. 1;

FIG. 4 is a left-side elevation view of the laundry appliance shown in FIG. 1;

FIG. 5 is a right-side elevation view of the laundry appliance shown in FIG. 1; and,

FIG. 6 is a rear elevation view of the laundry appliance shown in FIG. 1.

The features shown in dashed lines show portions of the design for illustrative purposes only and form no part of the claimed design.
